UNITED STATES PATENT OFFICE.

BENJAMIN F. MAYO, OF SALEM, MASSACHUSETTS, ASSIGNOR TO JAMES W. BROOKS, PRINCIPAL TRUSTEE, OF PETERSHAM, AND JOHN BROOKS, ASSOCIATE TRUSTEE, OF CAMBRIDGE, MASSACHUSETTS.

TRIMMING-MACHINE FOR BOOT OR SHOE WORK.

SPECIFICATION forming part of Letters Patent No. 609,519, dated August 23, 1898.

Application filed May 22, 1897. Serial No. 637,660. (No model.)

To all whom it may concern:

Be it known that I, BENJAMIN F. MAYO, of Salem, county of Essex, State of Massachusetts, have invented an Improvement in Trimming-Machines for Boot or Shoe Work, of which the following description, in connection with the accompanying drawings, is a specification, like letters and figures on the drawings representing like parts.

This invention has for its object to improve the construction and operation of that class of trimming-machines employed for boot and shoe work, my improvement consisting in combining with a rotary cutter and its shaft a spring-supported yielding table movable back and forth parallel to the axis of motion of the said shaft and its cutter, the said table being also adjustable, so that it in use may occupy a position more or less angular with relation to the axis of rotation of said shaft and cutter.

Figure 1 in top or plan view shows a sufficient portion of a trimming-machine to illustrate my improvements. Fig. 2 is a side elevation of the parts shown in Fig. 1, and Fig. 3 is a front or left-hand view of the parts shown in Fig. 1.

In the drawings let A represent the framework of a usual trimming-machine for boot and shoe work, said framework having bearings for a suitable rotating shaft B, provided at its front or left-hand end with the rand-guide a, a rotary cutter b, and a feather-edger composed of a ring c, having a series of bevel-ended fingers which enter the spaces between the blades of and rotate in unison with the cutter, said fingers acting against the tread-face of the heel being trimmed. This feather-edger by acting against the tread-face of the heel or sole end of the heel in the line of the cut being made by the blades of the cutter tends to keep the latter firmly up in position in the line where it is being cut, thus preventing the leather from spreading or rolling over to leave a feather or ragged edge.

The rand-guide a is provided at its outer surface with a beveled surface, (shown at the left in Figs. 1 and 2,) which during the action of the trimming-cutter rests against the up-

per lying on the last, it may be, and follows 50 the contour of the last during the trimming operation.

The framework receives a sleeve d, which is fixed thereon and constitutes one of the bearings for the shaft B. A spring e, surrounds the sleeve d, and beyond said spring the said sleeve is also surrounded by a sliding collar e', said collar having projecting from one side of it an arm e² to constitute a table-support entirely independent of the rand-guide. This table-support has pivoted upon it at e³, near the circumference of the rand-guide, a table e⁴, said table having a wing or projection e⁵, which is slotted at f to be entered by a clamp-screw f', screwed into the 55 arm e², said clamp-screw enabling the face of the table to be adjusted to any desired inclination with relation to the axis of rotation of the cutter b and its shaft. This collar, arm, and table are free to slide longitudinally 60 on or with relation to the shaft B independently of the rand-guide, and to prevent the rotation of said collar on the said sleeve I have provided the collar with a slot e⁶, which is entered by a pin 2, extended from said 65 sleeve d.

The front end of the sleeve d receives against it a spiral spring g, the opposite end of said spring acting against the hollow shank h of the feather-edger c, thus leaving said feather-edger free to be slid longitudinally on the shaft B to uncover more or less of the length of the teeth of the cutter, as may be required, to thereby adapt the cutter to trim a heel or sole of varying thickness.

The rand-guide a runs in a fixed path in the usual rand-crease or the space between the sole and upper, and the convexed edge portion a' of the rand-guide acts upon the upper lying, it may be, on the last, and at the 80 same time the feather-edger acts against the bottom or tread-face of the heel if a heel is being trimmed, or the sole if the heel is of the variety known as "spring-heel," or the face of the sole if the sole alone is being 85 trimmed, the said feather-edger yielding to the variations in thickness of the heel or sole, and the said table follows the feather-edger 90 95

as it adapts itself to varying thicknesses being trimmed.

The shoe the heel of which is being trimmed will first be pressed against the face of the table e^4 , and said heel or sole, as it may be, will be then pressed toward and against the cutter until the rand-guide enters the usual rand-crease, the edge of the heel or sole acting against the feather-edger and crowding it to the right, viewing Fig. 1, more or less, according to the thickness of the heel or sole, and during this operation the shoe will be turned more or less on or about said table.

If it should be desired to trim the heel at a defined angle, then the table may be adjusted by or through the set-screw f^2 to the required angle, and thereafter during the trimming operation the table will remain at the same angle.

In this invention the table is not swung up or down or turning about a pivot during the operation of trimming the heel.

Having fully described my invention, what I claim, and desire to secure by Letters Patent, is—

1. In a trimming-machine, a rotary shaft having an attached rand-guide, and a cutter; and a feather-edger loose on said shaft and having teeth to enter between the blades of the cutter, said feather-edger rotating with said cutter and being movable longitudinally on or with relation to said shaft; combined with an independent, spring-controlled table made movable in a line parallel with the axis of rotation of the said shaft, to follow the feather-edger in adapting itself to material of varying thickness, substantially as described.

2. In a trimming-machine for boots and shoes, a rotary shaft, a connected rand-guide, and a rotating cutter; a spring-controlled feather-edger rotatable with said cutter and adapted to be moved to and from said rand-guide by varying thicknesses of material being trimmed; combined with a table-support and a table made adjustable on said support, to thereby change its angle with relation to

the axis of said shaft, said table-support and table being movable in a line parallel to the axis of rotation of said shaft, and in unison with the feather-edger, substantially as described.

3. In a trimming-machine, a rotary shaft having an attached rand-guide, and a cutter; a feather-edger surrounding said shaft and rotatable therewith and with said cutter; combined with an independent table-support, and a table pivotally mounted thereon near the circumference of the said feather-edger, and a spring to keep the table pressed in a yielding manner toward the rand-guide, substantially as described.

4. In a trimming-machine, a rotary shaft having an attached rand-guide, and a cutter; a feather-edger surrounding said shaft and rotatable with it and said cutter; a spring surrounding said shaft and acting upon said feather-edger, to move it toward said cutter; combined with an independent table-support, and a table pivotally mounted thereon, and a spring to normally press said table-support toward said rand-guide, substantially as described.

5. In a trimming-machine, a rotary shaft having an attached rand-guide, and a cutter; a feather-edger surrounding said shaft loosely and rotated with said shaft through the said cutter, and a spring to move said feather-edger toward said cutter; combined with a table-support independent of said feather-edger and movable longitudinally with relation to the axis of said shaft, said table-support having pivoted upon it near the circumference of the rand-guide a table, and means to hold said table in adjusted position, substantially as described.

In testimony whereof I have signed my name to this specification in the presence of two subscribing witnesses.

BENJAMIN F. MAYO.
